UNITED STATES PATENT OFFICE.

WILLIAM J. CRUMPTON, OF EVANSTON, ILLINOIS, ASSIGNOR, BY MESNE ASSIGNMENTS, TO WILLIAM R. HEATH, OF BUFFALO, NEW YORK.

ACCOUNTING SYSTEM.

1,084,614.

Specification of Letters Patent.

Patented Jan. 20, 1914.

Application filed September 16, 1909. Serial No. 517,969.

To all whom it may concern:

Be it known that I, WILLIAM J. CRUMPTON, a citizen of the United States, residing at Evanston, in the county of Cook and State of Illinois, have invented certain new and useful Improvements in Accounting Systems, (Case 16,) of which the following is a full, clear, concise, and exact description, reference being had to the accompanying drawings, forming a part of this specification.

My invention relates to electrically controlled and automatically governed accounting systems, and is particularly applicable to systems of time-, wage-, job- and cost-accounting, where the entries made are generally but not necessarily functions of time.

The system which I have herein set forth as illustrating one embodiment of my invention, comprises individual as well as totalizing registers grouped and arranged to form substations. These substations are connected in multiple with a source of electric impulses and include differential motor mechanisms for discharging the entries, at the same time that they accumulate, into a generic receiving station. For the sake of simplicity I have shown the substations as discharging into a central station where all of the grand totals appear. It is obvious, however, that various stations may be interposed between the substations and the final receiving station.

The registers are actuated by means of a three-phase motor associated with each register. These motors are energized from a source of three-phase current impulses. The rate of actuation of any register is, of course, dependent upon the number of cycles impressed upon the associated motor in a predetermined period of time. I might say right here that when I use the term "cycle" in this connection, I mean a set of three impulses. These motors are adapted to actuate the registers in either direction according to the order in which the electrical impulses are impressed upon the different "phases" of the motor. I do not herein lay claim broadly to such a three-phase motor, since that is a feature claimed in my co-pending application Serial No. 498,547, filed May 26, 1909.

The differential motor mechanism herein shown (which I prefer to call a substation

unit) is so constructed that the cycles impressed upon it may cause a resultant motion of the armature equal to zero. There are various ways in which this may be carried out. In the particular form herein illustrated, a substation unit is provided with two sets of three-phase windings, one set being connected in circuit with the individual wage registers to actuate the armature in one direction; while the other set is connected with the registers at the central station and is adapted to actuate the armature in the reverse direction. Because of this characteristic mode of operation of these substation units, I have come to designate (and aptly, I think) the substations as ballistic substations. Specific details regarding the precise operation and function of these ballistic substations will follow in due course. I might here mention that one of the great features of these substation units is their remarkable simplicity,—there being a total absence of such mechanical encumbrances as differential gears.

In the system disclosed in my co-pending application above referred to, the rate controlling mechanism must be partially duplicated for each substation, if it is desired to have the rates prevailing in the various substations entirely independent of each other. Now, in the present system, this freedom or independence of rates between substations is secured by a single rate controlling mechanism for the entire system, the substations being connected in multiple with the source of impulses. Each substation is, of course, provided with a rate connecting-board for involving each workman's register with a particular rate. By varying the number of times that a wage register is connected during a predetermined period, different rates may be produced. Thus, a register whose circuit is closed twice as often as that of another register during the same period, will operate at twice the rate of that other register. In the system of this invention the time-, wage- and job-registers of each substation are arranged in series with the source of impulses. In order, however, to secure actuation of the time-registers at the same uniform rate, irrespective of the rate of actuation of the connected wage-registers, I have made provision whereby the time-registers will become locked after the proper number of impulses has been sent through

them in a given period, without in any way interfering with the further actuation of the wage-registers during that period. By means of a selector mechanism serially included in the connections between the source of impulses and the substations, the workmen's registers in any substation are successively selected for actuation, while the corresponding registers of all of the substations are selected for simultaneous actuation. I have already mentioned that the substation units receive impulses through the individual wage-registers tending to actuate the armatures in a certain direction. These impulses are what might properly be termed accumulating impulses. The impulses, which these substation units receive through their connections with the totalizing registers at the central station, I designate as transfer impulses, since they tend to cause rotation of the armatures in the reverse direction. If these opposing impulses occur simultaneously in a substation unit, there will be no motion of the armature, and for every accumulating impulse passing through the workmen's wage-registers, there will be a transfer impulse passing through the corresponding totalizing registers at the central station. The accumulating circuit connections are such that, as already mentioned, the corresponding wage-registers of the various substations will be actuated simultaneously. This means, of course, that the corresponding substation units will be simultaneously subjected to accumulating impulses. The transfer circuit connections, however, are such that the substations are connected successively with the grand total registers at the central station. This means that the corresponding units of the different substations are subjected one after the other to transfer impulses. The result of this arrangement is that a substation unit will, at one time, be subjected to accumulating impulses and transfer impulses concurrently and at another time receive the opposing impulses inter-currently. As already explained, when the opposing impulses take place concurrently, there will be no motion of the armature—at least the resultant motion will be equal to zero. However, when the opposing impulses take place intercurrently, the armature will be actuated in a certain direction under the influence of the accumulating impulses. After a predetermined amount of such rotation of the armature, the circuit is automatically closed through the transfer windings and the armature is rotated in the reverse direction an equal amount, whereby the same number of impulses that passed through the accumulating windings will be sent through the totalizing register at the central station. Thereupon the circuit through the transfer windings is automatically opened and the accumulating windings

may again produce rotation. These substation units really take the place of individual job-registers and might, in fact, be considered as such, except that they are not provided with any numeral wheels. They 70 are not intended to give any indications, but merely serve as channels for receiving and transferring individual wage-accumulations into the corresponding totalizing registers.

Many other characteristic features of my 75 invention will present themselves as the specification proceeds.

Referring to the drawings where the corresponding parts are indicated by the same reference characters, Figure 1 is a diagrammatic illustration of my invention showing the circuits and the various controlling devices for effecting the accumulation of the registers, Fig. 2 is a diagrammatic representation of the transfer circuits and controlling devices, Figs. 3, 4 and 5 are more or less diagrammatic indications of the differential motor mechanism, the armature being shown in the various positions it will assume under the successive energization of the windings, Fig. 6 is a view partly broken away of a register detail showing how the circuit through the register actuating device is automatically interrupted as the register passes through zero, Fig. 7 is a sectional side view taken on the line 7—7 of Fig. 6, and Fig. 8 is a side view of a substation unit showing the arrangement whereby the circuit through the transfer windings is automatically opened and closed after a 100 certain amount of rotation of the armature in either direction. Fig. 9 is a top view of the parts shown in Fig. 8.

I think that an understanding of the operation of my system will be greatly facilitated, if I first explain the construction and working of the differential motor mechanism as shown in Figs. 3, 4, 5 and 8. Calling attention to Fig. 3, the magnets 1, 2 and 3 and the armature A are so arranged that 105 if winding Aa is energized, the armature will be rotated counterclockwise into the position shown in Fig. 4. If next the winding Ab is energized, the armature will be rotated one step into the position in which it is 110 shown in Fig. 5. If now the winding Ac be energized the armature will receive another rotation in the same direction until it assumes a position identical with that shown in Fig. 3 so far as the angular disposition 115 of the armature blades is concerned,—that is to say, after actuation of the armature by the winding Ac, it will be again in a position to be acted upon by the winding Aa to commence a new cycle of rotations. It will be 120 seen, therefore, that by sending successive electrical impulses through the windings Aa, Ab and Ac, actuation of the armature is produced in a certain direction, indicated in the drawing as counterclockwise. A set of 130

three impulses may thus be considered a cycle. Considering now the outer set of windings shown in these figures, it will be apparent that if winding T_a be energized while the armature is in the position shown in Fig. 3, the armature will be rotated clockwise, as indicated by the outer pair of arrows, into the position shown in Fig. 5. Then if the winding T_b be subjected to a current impulse, the armature will begin another movement clockwise into the position in which it is shown in Fig. 4. If the cycle of impulses be completed by the energization of the third winding, namely that indicated by T_c , the armature will receive a third rotation clockwise until it assumes the position shown in Fig. 3. For purposes of designation, we will call the first set of windings, to-wit: indicated by A_a , A_b and A_c the accumulating windings; and the windings designated T_a , T_b and T_c , we will call the transfer windings.

In Fig. 1, where the registers as well as the substation units are indicated merely in a diagrammatic way, the accumulating windings of the substation units TW , WW and $SU1$ to $SU4$, of substation $S1$, and the corresponding units of substation $S2$ are represented by the lower sets of circles which are, as shown, connected in circuit. Each set of three circles represents the three accumulating windings of the substation unit to which they apply. In order to avoid confusion and to simplify Fig. 1 as much as possible, the three transfer windings of each substation unit are shown as three disconnected circles. In Fig. 2, on the other hand, where we are concerned merely with the transfer feature of the system, the accumulating windings are represented by disconnected circles in sets of three each, while the transfer windings are shown included in the transfer circuit connections.

Returning now to Figs. 3, 4 and 5, it will be apparent that with the armature in the position indicated in Fig. 3, the simultaneous energization of the windings A_a and T_a , will result in no rotation of the armature, for the reason that the effects of the windings upon the armature are equal and opposite. Similarly, if windings A_b and T_b are simultaneously energized, there will be no rotation of the armature, and the same is true if there is a simultaneous energization of the windings A_c and T_c . It will thus be seen that the windings of this motor mechanism may be energized in pairs in a way to cause no rotation of the armature,—at least, in a way such that the resultant rotation of the armature is zero for every cycle of impulses. It may happen that in the actual construction of the device the arms of the armature in occupying a position corresponding to that shown in Fig. 3, might be a trifle nearer to the core of one winding

than to that of another. The unbalancing might be sufficient to cause rotation of the armature even under the influence of opposing windings. For instance, referring to Fig. 3, we might suppose that the armature was in greater proximity to the core of winding A_a than to the core of winding T_a . Simultaneous energizing of these windings would cause the armature to be actuated by winding A_a substantially into the position in which it is shown in Fig. 4. The next pair of windings to be energized would be the windings A_b and T_b . The armature being in the position shown in Fig. 4, would suffer no movement for the reason that one of the arms of the armature is directly opposite the core of the winding T_b . The cycle would be completed by the simultaneous energization of windings A_c and T_c , which would cause movement of the armature clockwise from the position shown in Fig. 4 to the position shown in Fig. 3, which was the position of the armature at the beginning of the cycle. In any event, therefore, the effect of cyclically energizing the windings in pairs, as above described, will cause the resultant rotation of the armature to be equal to zero. Considering the motor as a unitary structure independent of its specific use in connection with the system, it will be evident to those skilled in the art that there are other ways for producing the ballistic effect upon the armature. For instance, instead of setting up fluxes which act upon the armature opposingly, each pair of opposing windings might be arranged upon the same core and so connected in circuit that the fluxes produced by the energization of these windings would be equal and opposite. In other words, the flux due to one winding might be made to neutralize that of the other, causing the resultant flux to be equal to zero. Or, but a single winding might be arranged upon each core with connections to two opposing sources of electromotive force. This would prevent current from flowing through the winding and there would be no flux to act upon the armature. Although I have illustrated only the first way of producing the desired effect upon the armature, I will have it understood that I do not, by any means, intend to limit myself to such a construction, as indicated in certain of the appended claims.

From the above description of my three-phase motor-mechanism, it will be clear that as long as the impulses are cyclically sent through the windings A_a , A_b and A_c , the armature will be rotated counterclockwise. Inasmuch, however, as these motor-mechanisms are not intended to give any indications of the entries accumulating therein from the wage-registers, as mentioned in the introductory part to the specification, I prevent extensive actuation of the armature un-

der the influence of the accumulating windings, by causing automatic closure of the circuit through the transfer windings after a predetermined amount of rotation of the armature by the accumulating windings. One convenient way of carrying this out is shown in Fig. 8, where the two contacts 4 and 5 control the circuit through the transfer windings, as diagrammatically indicated 10 in Fig. 2. The contact 5 is connected with the spring-arm 6 which engages the peripheries of the disks 7 and 8 and normally tends to separate the two contacts. The disk 7 is fixed upon the shaft 9 and is provided with 15 the stud 10 as well as with a cam surface 11, the latter being indicated in dotted lines in Fig. 8. The disk 8 is rotatably mounted upon the shaft 9 and has a slot 12 to accommodate the stud 10. On the shaft 9 is also 20 mounted the gear 13 which meshes with a smaller gear 14 carried by the armature shaft 15. With the parts in the position shown in Fig. 8, the circuit through the transfer windings is closed by the contacts 25 4 and 5 and the winding next to be energized will be the winding T_a which will move the armature one step in a clockwise direction, causing the gear 13 and fixed disk 7 to move counterclockwise. By virtue of 30 the pin and slot engagement between the fixed disk 7 and the loose disk 8, the latter will be dragged along by the disk 7 in a counterclockwise direction, as can be clearly gathered from Fig. 8. This clockwise rotation of the armature under the influence of 35 the transfer windings will continue until the slot 16 in the loose disk 8 comes directly under the projection of the spring arm 6 whereupon the latter will drop into said slot and 40 cause separation of the contacts 4 and 5. This, of course, throws the transfer windings temporarily out of commission and gives the accumulating windings a chance to predominate. The rotation of the armature by 45 the accumulating windings will be counterclockwise, as already explained. During this actuation of the armature the disk 7 will be rotated clockwise while the disk 8 will remain stationary. This is due to the 50 fact that the stud 10 on the disk 7 will travel in the slot 12 of the disk 8. During this clockwise rotation of the disk 7, the projection on the arm 6 will ride up the cam surface 11 until the disk is in the position in 55 which it is shown in Fig. 8, where the arm 6 is shown as raised on the highest portion of the cam surface. The contacts 4 and 5 will therefore be again closed. This will cause the transfer windings to be again energized 60 and the disks 7 and 8 will be rotated counterclockwise as above described to separate the contacts. This cycle of operation will be repeated as long as the two sets of windings are not energized concurrently. For 65 the sake of convenience and simplicity the

two sets of windings have, in Fig. 8, been shown as superposed. With this description of the operation of the substation unit, we are now in a position to turn our attention to the system as it is diagrammatically indicated in Fig. 1. Upon the time-controlled impulse-shaft IS is fixed the disk D provided with the single tooth 17 which is adapted to engage the Geneva wheel G. It will be seen that for every revolution of the disk D, the Geneva wheel is rotated one quarter of a revolution. The shaft IS is shown as consisting of two insulated portions, one of which carries the impulse-disks da , db and dc , while the other portion supports a set of similar disks $d'a$, $d'b$ and $d'c$. The selector-shaft SS, upon which the Geneva wheel is mounted, is shown as divided into a plurality of insulated sections upon which are mounted the selector-brushes SB. Associated with three of the selector brushes are the three phase motor selecting disks or commutators SDa , SDb and SDc . The fourth selector-brush has associated therewith the time-selector commutator TS which is similar to the other commutators. Upon the insulated end 18 of the selector-shaft is secured the cam 19 for periodically actuating the rate-controlled mechanism, as will be hereinafter explained. Of course, it is obvious that the necessary insulation of the parts may be accomplished in ways other than that shown. For the sake of simplicity of illustration the shafts IS and SS are shown in sections insulated from each other. Coöoperating with each of the commutators is a brush 20. A conductor 21a connects the brush of the disk da with the brush of the phase-selecting commutator SDa . The brush of disk db and the brush of the phase-selecting commutator Sdb are electrically connected by the conductor 21b, while the conductor 21c connects the brush of disk dc and the brush of the phase-selecting commutator SDc . 100

With regard to the reference characters used to designate the various impulse-disks and phase-selecting commutators, I will explain that I have added suffixes " a ," " b " and " c " to designate the different phases of each cycle of impulses. Thus, for instance, the impulse-disk da is the disk which connects the battery in circuit for the a -phase impulse of each cycle, while the phase-selecting commutator SDa connects the a -phase impulses to be sent through the register circuits. In this way, by paying attention to the suffixes used in certain of the reference characters, the different phases of the cycles of impulses may be traced in the 115 various circuit connections. 120

Each of the phase-selecting commutators consists of a plurality of insulated segments. For the sake of illustration the number of segments shown is four for each commuta- 130

tor. This is because, in the particular disclosure of this system, it has been assumed that the number of workmen in each substation is four. In any installation of my system, however, the number of segments in the phase-selecting commutators would be the same as the maximum number of workmen represented in any one substation. It is for the same reason that the selector shaft 10 SS makes one quarter of a revolution for every revolution of the impulse shaft IS. If the number of segments in the phase-selecting commutators are different, the connection between the two shafts would be 15 such that for every revolution of the impulse shaft IS, the selector shaft would be rotated through an angle sufficient to carry the brushes from one segment to the other.

A set of three bus-wires B1a, B1b and 20 B1c is connected with the segments No. 1 of the phase-selecting commutators SDa, SDb and SDc respectively. To this set of bus-wires is connected the workman's individual wage-register 101w and the workman's time-register 101t, which registers, it 25 will be observed, are serially connected. It may be supposed that these registers are assigned to workman No. 101 of substation S1. A similar set of bus-wires B2a, B2b and 30 B2c is connected with segments No. 2 of the phase-selecting commutators SDa, SDb and SDc, respectively. To this set of bus-wires are connected the wage-register 102w and the time register 102t, which may 35 be supposed to be assigned to workman No. 102 of the same substation. In a similar manner the remaining sets of bus-wires are connected to the remaining segments of the phase-selecting commutators. In other 40 words, a set of bus-wires leads from every workman's wage and time register in a substation to the phase-selecting commutators. It will be observed, however, that the registers of corresponding workmen in the various 45 substations are connected to the same set of bus-wires. For instance, in substation S2, wage-register 201w and the associated time register 201t (which registers may be assumed to be assigned to workman No. 201), 50 are connected to the same set of bus-wires as the registers assigned to workman No. 101. Similarly, the registers assigned to workman No. 102 of substation S1 are connected in multiple with the registers assigned 55 to workman No. 202 of substation S2.

The workmen's individual wage-registers and time-registers are provided with ordinary numeral wheels. The actuation of 60 these registers is accomplished by a three-phase motor-device such as I have previously explained in connection with Figs. 3, 4 and 5, except that only one set of windings is required, let us say the set indicated 65 in these figures by the reference characters

Aa, Ab and Ac. As previously explained, by cyclically energizing these windings one after the other, continuous rotation of the armature will follow. The rate of actuation will depend upon the frequency of the impressed impulses. Or, one might use the three-phase motor which I have shown and described in my copending application above mentioned. From the workmen's wage- and time-registers, the circuit connections lead 70 to conductors C1, C2, C3 and C4 which connect respectively with segments Nos. 1, 2, 3 and 4 of the register-selecting commutator WD. In conductors C1 to C4 are located the workmen's "in" and "out" switches S. 80 These are the switches which the workmen operate to throw the registers either into operation on arriving or out of operation upon leaving.

Associated with the selecting commutator WD is the brush SB fixed upon the substation selector shaft SSS which receives motion from the selector shaft SS through the medium of gears 22. Besides the commutator WD for selecting the individual time- and wage-registers for connection, the substation selector mechanism comprises also the commutator JD for selecting the substation units and the commutator RD for successively selecting the rates. A brush-arm is associated with each of those commutators. It will be observed that the commutators of the substation selector mechanism are similar to the phase-selecting commutators and that the brushes of the two sets of commutators are so disposed on their respective shafts that corresponding segments are engaged at the same time. Considering the parts, as shown in Fig. 1, it will be seen that the brushes of the phase-selecting commutators and the disks of the substation selector mechanism are all in engagement with segments No. 1 of their associated commutators. When the selector-shaft SS is actuated to move the brushes carried thereby from segments No. 1 to segments No. 2, the substation selector shaft SSS will be rotated to carry the brushes thereon from segments No. 1 to segments No. 2 of the associated commutators RD, 95 JD and WD. The brushes on the shaft SSS are shown insulated from each other by being mounted upon insulated sections of the shaft, similar to the mounting of the brushes on the selector shaft SS. From the segments of the commutator JD lead the conductors 31, 32, 33 and 34 which terminate in plugs jp1, jp2, jp3 and jp4, respectively. These plugs consist each of a pair of spring contacts which are normally closed, as shown in three of the plugs in Fig. 1. When, however, a plug is inserted in one of the openings in the jacks of the job switchboard JS, the contacts are forced apart, thus breaking 100 the connection between the conductors 31, 105 32, 33 and 34. The conductors 31, 32, 33 and 34 are connected to the conductors C1, C2, C3 and C4, respectively, of the register-selecting commutator WD. The conductors C1, C2, C3 and C4 are connected to the conductors 110 31, 32, 33 and 34, respectively, of the register-selecting commutator WD. The conductors 31, 32, 33 and 34 are connected to the conductors 115 31, 32, 33 and 34, respectively, of the register-selecting commutator WD. The conductors 31, 32, 33 and 34 are connected to the conductors 120 31, 32, 33 and 34, respectively, of the register-selecting commutator WD. The conductors 31, 32, 33 and 34 are connected to the conductors 125 31, 32, 33 and 34, respectively, of the register-selecting commutator WD. The conductors 31, 32, 33 and 34 are connected to the conductors 31, 130 32, 33 and 34, respectively, of the register-selecting commutator WD.

to 34 and the common conductor 35 which leads to the accumulating windings of the substation unit WW. Each strip of jacks in the switchboard JS is representative of a job. 5 Thus, a plug inserted in jack strip $js1$ would connect a workman with job No. 1; a plug inserted in jack-strip $js3$ would connect a workman with job No. 3; and so on. The number of jacks in any one strip may, of course, be sufficient to accommodate all of the workmen in that department of which the substation is representative; so that all of the workmen in that department may be assigned to one and the same job. 10 15 From the jack-strips of the job-switchboard JS lead conductors 41, 42, 43 and 44 to the accumulating windings of substation units SU1, SU2, SU3 and SU4, respectively. At their other ends, these windings of the substation units WW and SU1 to SU4 are connected to the three conductors 36a, 36b and 36c. The accumulating windings of the substation unit TW are included in the connections between the conductors 36a, 20 25 36b and 36c and the set of bus-wires Ba, Bb and Bc, so that the accumulating impulses passing through any one of the substation units WW and SU1 to SU4 will also be impressed upon the accumulating windings of the substation unit TW. The latter, therefore, serves as a totalizing unit for the other units of the substation; or it might, perhaps, be better to state that the unit TW receives impulses at a rate corresponding to the sum 30 35 of the rates at which the impulses pass through the workmen's individual wage-registers 101w, 102w, etc. As the substation units in this system are nothing more than electric motors, the total wages earned 40 will not be indicated by TW but will be transferred, as will appear later, into a grand total register at the central or final station. The substation unit WW is also a totalizing unit in that it receives impulses 45 that pass through the wage-register of the workman whose switch has been thrown to the "in" position but who has not been assigned to any particular job. It is, of course, obvious that when a workman arrives in the morning and throws in his switch he should not be deprived of his wages during the time in which he has not been assigned by the foreman to some job. The substation unit WW has therefore been 50 55 provided to receive the impulses that pass through a workman's register when he is not connected with any particular job. In such a case a workman's job-plug will be out of position on the switchboard JS and 60 the spring contacts of the plug $jp1$ will be closed as is the case with the plugs $jp2$, $jp3$ and $jp4$ in Fig. 1. When a plug is in the "out" position the impulses passing through the connected wire 31, 32, 33 or 34 from 65 the connected wage-register will pass

through the job-plug into the accumulating windings of the unit WW by way of the common wire 35. When, however, a plug is inserted in the job-switchboard, the impulses passing through the connected wire will not enter the unit WW but will pass into the proper substation unit SU1 to SU4. The unit TW receives the impulses that pass not only through the job-units SU1 to SU4 (as they may be termed) but also those passing 70 75 through the waste wage unit WW.

The bus-wires Ba, Bb and Bc act as common conductors for the various substations which are connected in multiple thereto. Thus, in Fig. 1, the substation unit TW' is connected to the bus-wires in parallel with the corresponding unit TW of the substation S1. The substation unit TW' is so connected with the other units of that substation as to receive all of the impulses passing 80 85 therethrough. In this way the units TW, TW', etc., act as totalizers of the number of impulses passing through the other substation units. The brushes 20 of the impulse disks $d'a$, $d'b$ and $d'c$ are connected with the bus-wires Ba, Bb and Bc, respectively. It will be observed that the segments of the disks $d'a$, $d'b$ and $d'c$ bear the same angular relation toward their associated brushes as the segments of the disks da , db and dc 90 95 bear toward their brushes. That is to say, when a segment of disk $d'a$ is in engagement with its brush, a corresponding segment of the disk da will make contact with its associated brush. The only reason why the segments of corresponding disks are shown displaced by an angle of 180 degrees is because, for the convenience of illustration, one set of brushes is shown displaced 180 degrees with respect to the other set of brushes. The 100 105 segments of the disks $d'a$, $d'b$ and $d'c$ are connected with one side of the battery through the conductor 37, while the segments of the disks da , db and dc are connected to the opposite side of the battery B 110 115 through the conductor 38. This brings us to the rate-controlling mechanism and the circuit connections therefor. From the common conductor 39, which is connected with one side of the battery B, leads the wire 40 120 which terminates in the common bus-wire 50. To this wire 50 is connected, at each substation, one side of the winding 51 of a solenoid switch having a movable core 52. The other side of the winding is connected 125 through conductor 53 with the brush of the rate-selecting commutator RD. When the winding is energized the iron core is actuated to close the contacts 54 and 55, thereby electrically connecting the brush of selector commutator WD with the brush of selector commutator JD through the conductor 56 and the switch S'. To the segments of the rate selecting commutator RD are connected conductors 61, 62, 63 and 64 which terminate 130

in rate plugs rp_1 , rp_2 , rp_3 and rp_4 . These plugs are associated with a rate connecting board consisting, in the present instance, of four series of multiple jacks indicated, respectively, by rs_1 , rs_2 , rs_3 and rs_4 . Each of these series of strips of rate-jacks is adapted to be connected in the circuit of a rate disk. There is a rate-connecting board for every substation, the corresponding series of jacks being connected in multiple to the same conductor. Thus, the first strip of jacks of each substation is connected with the common conductor RC_1 ; the second strip of jacks is connected with the conductor RC_2 , and so on. The conductor RC_1 is connected with the brush which is associated with the rate controlling disk R_1 ; the conductor RC_2 is connected with the brush associated with the next rate-controlling disk, namely, that indicated by R_2 , the conductor RC_3 is connected with the brush of the next higher rate-controlling disk, R_3 ; while the conductor RC_4 is connected with the brush of the rate-controlling disk R_4 . These rate-disks are fixed upon the rate-shaft RS which also carries the ratchet-wheel 65 adapted to rotate with the shaft. With the teeth of this ratchet wheel co-operates the pawl 66 pivotally supported upon the arm 67 which is rotatably mounted upon the shaft RS beside the ratchet wheel. A spring 68 normally holds the pawl in engagement with the teeth of the ratchet wheel, while the spring 69 connected at one end with the outer portion of the arm 67 normally tends to rotate said arm in a clockwise direction. A roller 70 journaled on the arm 67 engages the periphery of the cam 19 which, as already described, is fixed upon the selector shaft SS . This cam is provided with a cam surface 71 which permits the arm to be drawn backward by the spring 69 and also causes forward actuation of the arm to move the ratchet wheel 65 through a distance equal to the space of one tooth. According to the position of the parts shown in Fig. 1, the roller has just been forced up the cam surface and has actuated the ratchet wheel 65 . The shaft RS is connected with conductor 72 , which, in turn, is connected with one side of the battery through conductor 73 .

The precise manner in which the rate-mechanism controls the various rates at which the registers are actuated will be better understood after the operation of the system has been described, which description is now in order.

For the tracing of the circuits that enter into the operation of the system, let us select some particular register, say for example the individual wage- and time-registers assigned to workman No. 101. These are the registers $101w$ and $101t$. The brushes of the selector shaft SS have just been moved into engagement with segments No. 1 of the asso-

ciated phase-selecting commutator, which means that the brushes on the substation selector shaft SS are also in engagement with segments No. 1 of their respective selector commutator. Let it be also supposed that the workman's rate-plug rp_1 has been inserted in a jack of the strip rs_1 which will connect the workman with the rate represented by the disk R_1 . The workman's switch S is moved to an "in" or closed position. As the impulse shaft IS is rotated in the direction indicated by the arrow, the segment of impulse disk da will be the first one to engage its brush. At the same time the segment of the corresponding disk $d'a$ will make contact with its brush. With the parts in this position the following circuit will be closed through the winding of the solenoid switch and through the rate-controlling mechanism: from one side (which we may consider the positive side) of the battery B , the current will flow through conductor 39 to conductor 40 , through the winding 51 of the solenoid switch to conductor 53 , through the brush of commutator RD to segment No. 1 of that commutator to conductor 61 , rate-plug rp_1 , one of the jacks of strip rs_1 , conductor RC_1 , thence to disk R_1 (one of whose segments engages the associated brush), shaft RS , conductor 72 , and thence through conductor 73 to the other side of the battery. The winding 51 being energized, actuates the iron core 52 to close the contacts 54 and 55 . This completes the circuit for the a -impulse of the cycle through the registers $101w$ and $101t$ as follows: from one side of the battery B (which we may consider as the positive side) to the conductor 38 , from there to segment of disk da , conductor $21a$, segment No. 1 of the a -phase selecting commutator SDa , from there to bus-wire $B1a$, through the a -phase winding of time-register $101t$, then serially through the a -phase winding of the workman's individual wage register $101w$, then across the contacts 74 and 75 of the wage-register, from there to conductor $C1$, switch S , thence to segment No. 1 of the selector commutator WD , across the associated brush to conductor 56 , across the contacts 54 and 55 which have been closed by the solenoid switch, then across switch S' , across the brush of the selector commutator JD to segment No. 1 of that commutator, then through conductor 31 to the job-plug jp_1 , thence through the conductor 41 to the a -phase winding of substation unit SU_1 , conductor $36a$, through the a -phase winding of the totalizing unit TW from there to the bus-wire Ba , thence from brush 20 of the impulse disk $d'a$ to the segment of that disk, and from there through the conductor 37 back to the other side of the battery. As the impulse shaft continues to rotate, the segments of disks db and $d'b$ will next en-

gage their respective brushes in order to close the circuit for the *b*-impulse of the cycle through the same registers and substation units. Then when the segments of the disks *dc* and *d'e* come into engagement with their respective brushes, the circuit connections will be closed for the *c*-impulse of the cycle. The circuits for the *b*-phase and *c*-phase impulses are so analogous to the circuit which has been traced in detail for the first impulse of the cycle that it is not believed necessary to trace the circuits in detail for the other phases of the cycle. Those circuits will be readily understood from the circuit of the first impulse of the cycle. It will, of course, be realized that as the impulse shaft rotates to bring the segments of the various impulse disks successively into engagement with their brushes, the selector shaft SS, the substation selector shaft SSS, as well as the rate shaft RS remain stationary. However, as the impulse shaft IS completes the revolution, the tooth 17 of the gear D will, through the medium of the Geneva wheel G, impart to the selector shafts SS and SSS one quarter of a revolution so as to bring the brushes into engagement with the segments No. 2 of the various commutators. Thereupon the cycle of impulses will be sent through the registers 102*w* and 102*t* and through one of the substation units SU1 to SU4, depending upon the particular jack-strip in the switchboards JS with which the jack-plug *jp2* (which is assigned to workman No. 102) has been associated. Otherwise, the circuits through the registers belonging to workman No. 102 will be the same as the circuits which have been traced in connection with the registers of workman No. 101.

For the sake of having a clear understanding of the mode of operation of the rate-controlling mechanism, it has been assumed that the workman receives one cent in wages for every cycle of impulses sent through his register and that a register is selected for connection once every two minutes, or, as it is commonly put, a workman is "picked up" once in every two minutes. The impulse shaft IS will, therefore, make two revolutions per minute, which will cause the selector shafts SS and SSS to make one revolution every two minutes. The ratchet wheel 65 is provided with thirty teeth. Once in every revolution of the shaft SS, the ratchet wheel, as already explained, will be moved the distance of one tooth which is one-thirtieth of a revolution. From this it follows that the rate-shaft will make one revolution per hour. The rate-disk R1 has been designed to represent a rate of ten cents per hour. It will be remembered that the workman is selected for connection once during every revolution of the shaft SS. Now, inasmuch as this shaft makes thirty revolutions per hour to

send thirty cycles through the circuits of the system it follows that if a rate-disk were in a circuit closing position during every one of those thirty revolutions of the shaft SS, such a disk would represent a rate of thirty cents per hour. However, by so constructing the disk that during certain revolutions of the selector shaft it remains in an open position, any desired rate may be secured. Thus a disk to represent ten cents per hour would occupy a closed position only during ten revolutions of the shaft SS every hour. Such a disk is the rate disk R1. It will be observed that this disk is provided with ten segments equally distributed around the periphery of the disk. This means that the disk will be in a circuit closing position during every third revolution of the selector shaft. Considering that the disk will close the circuit during the first revolution in every hour of the shaft SS, the ten revolutions during which the disk would cause the circuit of the connected register to be closed, would be the following: 1st, 4th, 7th, 10th, 13th, 16th, 19th, 22nd, 25th and 28th. During the intervening revolutions, the brush of the disk R1 would engage the insulation between the segments. The rate disk R2 represents a rate of fifteen cents per hour. This is obtained by so constructing the disk that 15 of the 30 revolutions per hour of the selector shaft SS are lost, as it were. That is to say, during those 15 revolutions, the brush of the disk will engage the insulation between the segments. It will be observed that there are certain alternate segments, five in number, which are narrower than the five interposed segments. The object of this arrangement is to have each of the five narrow segments close the circuit during one revolution of the impulse shaft, while the wide segments close the circuit during two consecutive revolutions of the impulse shaft. Accordingly, there will be fifteen revolutions during which the rate-disk R2 will occupy a circuit-closing position, those revolutions being the following: 1st, 4th, 5th, 7th, 10th, 11th, 13th, 16th, 17th, 19th, 22nd, 23rd, 25th, 28th and 29th. The rate disk R3 has been designed to represent a rate of 20 cents per hour. This is obtained by causing the disk to be in open-circuit position during 10 out of the 30 revolutions per hour of the selector shaft SS. Each of the ten segments with which the disk is provided allows the circuit to remain closed for two consecutive revolutions of the selector-shaft, thus closing the circuit for twenty cycles. This disk assumes an open-circuit position every third revolution of the impulse shaft, these revolutions being the following: 3rd, 6th, 9th, 12th, 15th, 18th, 21st, 24th, 27th, 30th. This, of course, is on the assumption that during the first two revolutions the brush is in contact with one of the segments.

If, at the beginning of the hour, the brush engages an insulated portion of the disk, the ten "lost" revolutions would be distributed accordingly. In any case the result is precisely the same. Concerning the highest rate-disk R4, which represents a rate of twenty-five cents per hour, it will be observed that it is provided with five wide segments separated by relatively narrow pieces 5 of insulation. This disk assumes a circuit-opening position during five of the thirty revolutions of the selector-shaft SS. If we consider that at the beginning of the cycle 10 of revolutions the brush of this disk is at the commencement of a segment then the five revolutions which are omitted by the disk are the following: 6th, 12th, 18th, 24th and 15 30th.

I have gone into the above detailed explanation of how the rate-mechanism shown 20 in the drawings has been designed to represent certain rates, in order to make clear the theory of operation of the rate-mechanism. It will now be understood that, given 25 a certain period, say one hour, the rate at which a register will be actuated depends upon the number of times during which the circuit of that register has been closed during every hour. The rate-disks control the 30 register circuits through the instrumentality of the solenoid switch which controls the contacts 54 and 55 included in a common conductor of the register circuits of each substation. As may be seen from Fig. 1, 35 the circuit of any one wage-register can be completed only through the conductor 56. Unless the winding 51 of the solenoid switch is energized by one of the rate-disks, the register circuit will remain open. There is 40 a rate plug for every workman, and the workman's rate-disk is selected simultaneously with the selection of his individual wage- and time-registers. Thus, in Fig. 1, the registers assigned to workman No. 101 45 are selected by the brushes of the commutators WD and JD engaging the associated segments No. 1. At the same time the brush of the selecting commutator RD is in engagement with segment No. 1 with which 50 the workman's plug is connected. If, while the workman is thus selected for connection with the rate mechanism, his particular rate-disk is in circuit closing position, the contacts 54 and 55 will be closed and an impulse 55 will be sent through his registers. On the other hand, if the rate-disk is in a position in which the associated brush engages the insulation, the circuit through the workman's register will remain open.

60 Inasmuch as the workman's individual wage-register and time-register are connected in series, it stands to reason that some provision must be made for securing a uniformity of rate of actuation of the time register, irrespective of the rate at which the associated

wage-register may be actuated. For, the function of the time-register is to indicate lapsations of time and should not be influenced by the rate of actuation of the connected wage-register, since that rate is arbitrarily determined and may be varied whenever desired. To render the rate of actuation of the time registers proportional to the lapsed time, no matter what the rates of actuation of the connected wage-registers may be, I provide 70 the actuating device of each time-register with a locking winding, the object of which is to lock the register against actuation beyond a certain amount during every hour.

In Fig. 1 it will be observed that the time-registers are diagrammatically shown as being provided with three windings connected at one end to the bus-wires B1a, B1b, B1c, and B2a, B2b, B2c, etc. On one of the cores of the three-phase motor which actuates the time-register, there is an additional winding. This winding, in Fig. 1, is indicated as being carried on the same iron core as the c-phase winding. I might perhaps be better able to explain the locking function 80 of this winding if I again direct attention to the diagrammatic illustrations in Figs. 3, 4 and 5. If in these figures we imagine the windings Ta and Tb removed, we get the precise mechanism for actuating the time-registers. It has already been described how 85 rotation of the armature is produced by sending a cycle of impulses successively through the windings Aa, Ab and Ac. Now, if after the momentary energization of 90 the c-phase winding Ac, the additional winding Tc should be energized, the armature would remain in the position in which it is shown in Fig. 1 so long as that winding remains energized. The energization of either 95 the winding Aa, Ab or Ac would not affect the position of the armature. In other words, so long as the extra winding Tc remains energized, the armature is locked 100 against movement. In Fig. 1 the locking 105 windings of the time-registers 101T, 102T, etc., are included in the connections L1, L2, L3 and L4 respectively. The locking windings of corresponding time-registers in the various substations are included in series in 110 the same connections. For instance, the locking windings of the time-registers 101t and 201t are serially connected with the conductor L1. The locking windings of the time registers 102t and 202t are serially connected with the conductor L2, and so on. One end of the conductors L1, L2, L3 and 115 L4 is connected with segments Nos. 1, 2, 3 and 4, respectively, of the selector commutator TS. At their other end these conductors are joined to the common conductor 120 39. The circuits of the locking windings of the different time registers are controlled by the time-locking disk TL fixed 125 upon the rate-shaft RS. In the particular 130

example illustrated, it has been assumed that every cycle of impulses passing through the time-registers represents one-tenth of an hour,—this being a very convenient way of indicating the time. In other words, the cycles pass through the time registers at the rate of one every six minutes. This means that during every revolution of the rate-shaft RS the connected time-registers must receive no more than ten cycles although mean the associated wage-register may receive fifteen, twenty, twenty-five or any number of cycles depending upon the rates involved. It is the function of the time-locking disk TL to so control the circuit of the locking winding of a connected time-register, so that the same will receive only ten effective cycles of impulses every hour. Inasmuch as the rate-disk R1 permits only ten cycles per hour to pass through the register operating at a ten cent rate, the locking circuit of such a register will not come into play. Consequently, whenever a segment of the disk R1 engages with the associated brush, the brush of the time-locking disk will engage an insulated section. Let us suppose that a register is operating at the rate of fifteen cents per hour, and is, therefore, connected with the rate-disk R2. In that case, whenever the brush of rate-disk R2 engages one of the five narrow segments, the brush of the time-locking disk TL will engage an insulated section. The relative angular disposition of the wide segments on the rate-disk R2 and the segments of the disk TL is such that for one of the two consecutive revolutions during which the brush of the rate disk remains in engagement with each one of the wide segments, the brush of the time-locking disk will be in engagement with a segment, but will engage an insulated portion of the disk for the other revolution. In consequence, the circuit through the locking winding of a time-register whose associated wage-register operates at a fifteen cent rate will be closed and the register locked against the influence of five of the fifteen cycles which pass through the wage-register every hour. In a similar manner does the disk TL operate to close the circuit of the locking disk for ten of the twenty cycles which the rate-disk R3 allows to pass through the connected register. When a register operates at a twenty-five cent rate, the time-locking disk closes the circuit for fifteen cycles every hour. We can readily trace one of the locking circuits by supposing that the brush of the time-locking disk is in engagement with one of the segments. The selector-brushes being in engagement with segments No. 1 of the various selector commutators, the locking circuit will be completed through the corresponding time-registers 101 t , 201 t , etc., as follows: from one side 65 of the battery to conductor 39, thence to the

conductor L1, then serially through the locking windings of the registers 201 t and 101 t , from there to segment No. 1 of the time-selector commutator TS, then through the associated brush to conductor 86, from there to the disk TL, shaft RS, conductor 72, conductor 73 and back to the other side of the battery B. As the selector shaft SS is rotated, the brush of the selector-commutator TS will engage the other segments 75 successively, thereby successively connecting the other time-registers of each substation with the time-locking disk.

In explaining the mode of operation of my system as shown in Fig. 1, and tracing the various circuit connections, I have made specific reference to substation S1 only. I do not deem it necessary to repeat the above description with reference to the second substation S2, or any other substations, for the reason that the circuit connections are merely duplicated for the various substations. Therefore, a detailed description with reference to any one substation is sufficient for a complete understanding of my invention. The only thing that remains to be said in connection with Fig. 1, is about the clearing circuit of the wage- and time-registers. It may sometimes be desired to set these registers to zero. This is accomplished by reversing the direction of rotation of the shaft IS and throwing the switches S' into engagement with the contacts 76. By reversing the direction of rotation of impulse shaft IS, there is a reversal of the order in which the impulses are impressed upon the windings of the three-phase motors that actuate the wage- and time-registers. This will cause the armatures of the registers to rotate in a decumulating direction to bring 105 the numeral wheels back to their zero position. It is obvious, however, that the registers might be set to zero by forward actuation. The clearing circuit for one of the impulses may be traced through the registers 110 101 t and 101 w as follows: from one side of the battery B, to conductor 38, to disk da, conductor 21a, segment 1 of selecting commutator SDa, registers 101 t and 101 w , contacts 75 and 74, conductor C1, switch S, segment 1 of selector commutator WD, conductor 56, across the contacts 54 and 55, switch S1, contact 76, conductor 77, conductor 78, conductor 73 to the other side of the battery. The clearing circuits for the 120 other phases of the impulse cycle and the other registers may be traced similarly. As a register is brought back to zero, the contacts 74 and 75 are automatically opened to break the circuit through the register and thereby prevent the same from going beyond zero. There are many ways in which this may be accomplished, one simple way being shown in Figs. 6 and 7. The highest order wheel has connected therewith a disk 79 pro- 130

vided with a cam portion 80. With the disk 79 coöperates an arm 81 having slotted engagement with the shaft 82 and being provided with a pin or stud 83. This arm abuts at its upper end against the contact 74. The angular position of the cam portion 80 with respect to the numeral wheels is such that as the register passes through zero, the cam portion 80 engages the pin 83. This moves the arm 81 to separate the contact 74 from the associated contact 75 and prevents actuation of the register beyond zero, or rather, to speak more accurately, beyond the "nines" position. In order to place the registers in condition for normal operation after being actuated reversely to the "nines" position it is necessary to give the registers a forward actuation sufficient to bring them from the "nines" to the zero position. There are several ways in which this might be done, but one of the simplest is to cause a cycle of impulses to be sent through the cleared registers. To accomplish this, the workmen's wage and central station registers are provided with an additional contact 125 adapted to coöperate with the contact 74 to close the circuit when the contact 74 is thrown out of engagement with the contact 75 as the register wheels pass to the "nines" position. The additional contacts 125 are connected with a common conductor 126 which leads to the battery through a suitable switch 127. Upon properly manipulating this switch in connection with the forward run of the gear controlling contact mechanisms, an electrical cycle may be sent through the proper registers, thus causing them all to indicate zero and at the same time close their normal forward running contacts. This places the registers in condition for receiving the register routine entries.

We will now direct our attention to the transfer operations of my system. I have stated in the fore part of this specification that the substation units are simply motors with no registers and no differential gears, serving merely as a medium for causing actuations equivalent to those of the connected wage-registers to be transferred into the total registers at the central station. I might say that these substation units act as circuit controlling devices which permit a cycle of impulses to pass through the proper totalizing register for every cycle that passes through the corresponding wage registers. The operation of the substation units has already been explained in the description of Figs. 3, 4, 5 and 8, and we saw there that the armature remains stationary when the accumulating windings are energized concurrently with the transfer windings, and that it is rotated back and forth when the two sets of windings are energized inter-

will take up a consideration of the circuits in which the transfer windings are included. The broken-away portion of the shaft shown at the left of Fig. 2 is supposed to be the upper end of the impulse shaft IS as shown in Fig. 1. The bevel gear 84 fixed upon the end of the impulse shaft engages the bevel gear 85 fixed upon the transfer impulse shaft TI, the gear ratio between these gears being respectively 1 to 2, so that the shaft 70 TI will make one revolution to every two revolutions of the shaft IS. This ratio, however, will vary in accordance with the number of substations. For the sake of simplicity but two substations have been shown 75 in the drawings. The reason for this gear ratio will presently appear. On the shaft TI are fixed three sets of transfer impulse-disks consisting of three disks each. The first set of disks, indicated by t_c , t_b and t_a , 80 is to connect the units of substation S1 with the source of impulses, while the second set of disks t'_c , t'_b , t'_a is adapted to connect substation S2 with the source of current. The third set of disks t''_c , t''_b , and t''_a is 85 to afford a return path to the battery for the various impulses. The a -, b - and c -phases of the transfer windings of the units in substation S1 are connected, respectively, to the conductors 100a, 100b and 100c. It will be 90 observed that in the case of the transfer windings, the a -phase winding occupies the same position as the b -phase of the accumulating windings. The b -phase of the transfer windings occupies the same position as 95 the a -phase of the accumulating windings, while the c -phase of the transfer windings occupies the same position as the c -phase of the accumulating windings. This is in accordance with what has been explained in 100 connection with Figs. 3, 4 and 5, where it will be observed that the accumulating windings occupy the positions in the order of a , b and c , while the transfer windings are arranged in the order of b , a and c . The 105 conductors 100a, 100b and 100c are connected with the brushes of the transfer impulse-disks t_a , t_b and t_c respectively. The different phases of the transfer windings of the units in substation S2 are connected to 110 the conductors 200a, 200b and 200c in a manner similar to the connection of the units in substation S1, to the corresponding bus-conductors 100a, 100b and 100c. Bus-conductors 200a, 200b and 200c are connected, respectively, with the brushes of the impulse disks t'_a , t'_b and t'_c . The corresponding units of the various substations are connected in multiple to the proper grand total 115 registers. Thus the units TW and TW' are connected to the conductor w which leads through the switch 90 to the grand total wage-register GTW. Similarly, the transfer windings of the waste wage units WW and WW' are connected in multiple to the 120 125 130

conductor ww which leads through the switch 90 to the total waste wage-register TWW. By following out the connections of the other corresponding units of the 5 substations, namely those indicated by SU1, SU2, SU3 and SU4 of substation S1 and units SU'1, SU'2, SU'3 and SU'4 of substation S2, it will be found that they are connected respectively with the job-total- 10 registers JT1, JT2, JT3 and JT4. I do not deem it necessary to trace every one of these circuits for the reason that they are similar to the circuits just traced for the units TW, TW', etc., and are furthermore apparent 15 from a mere inspection of Fig. 2. All of the totalizing registers JT1 to JT4 are connected in multiple to the bus-conductors 300a, 300b and 300c.

Let us now trace one of the transfer circuits in the operation of that portion of my system shown in Fig. 2. For the sake of simplicity we will take substation unit SU1. As the shaft TI is rotated in the direction indicated by the arrow, the segment of disk 25 ta will be the first one to engage its associated brush. At the same time, however, the brush of disk $t'a$ will come into contact with one of the segments of that disk. The 30 switches 90 and 91 being in the position indicated, the battery circuit will be completed through the substation unit as follows: from one side of the battery B' (which we may call the positive side) an impulse will flow through conductor 92, to the disk 35 ta , thence through conductor 100a, through the a -phase transfer winding of the substation unit SU1, from there by way of conductor 93 to conductor $j1$, across the switch 90, through the a -phase winding of job- 40 total register JT1, conductor 101a, common conductor 300a, switch 91, disk $t'a$, insulated section ti of the shaft TI and by way 45 of conductor 94 back to the battery. As the shaft TI continues to rotate, the circuit 50 will be next completed through the disks tb and $t'b$ which will cause the b -impulse to pass through the connected substation unit and totalizing register. Then the circuit 55 will be closed by the disks tc and $t'c$ whereby the c -impulse will pass through the circuit. A cycle of impulses will therefore 60 pass through the substation unit SU1 and the job-total register JT1 during one half a revolution of the shaft TI. During the 65 second half of the revolution of that shaft, a cycle of impulses will be sent by way of the disks $t'a$, $t'b$ and $t'c$ through the units of substation S2. The disks $t'a$, $t'b$ and $t'c$ will coöperate also with the disks $t'a$, etc., to close the circuit in proper order for 70 the three-phase impulses. The disks $t'a$, etc., are capable of coöoperating with both the disks ta , etc., and the disks $t'a$, etc., by being each provided with two diametrically

opposite segments. It will be observed that 65 the angular position of the segment on disk ta is diametrically opposite to that of the segment on the corresponding disk $t'a$. This diametric position also obtains with the segments of the disks tb , $t'b$, tc and $t'c$. Moreover, the various angular positions occupied 70 by the total segments on the disks $t'a$, $t'b$ and $t'c$ are respectively identical with the angular positions occupied by the pairs of disks $ta-t'a$, $tb-t'b$ and $tc-t'c$. 75

From the circuit connections above described, it will be apparent that the units of any one substation are concurrently "picked up" for transfer, while the substations themselves are selected successively for 80 connection. The arrangement and number of transfer impulse disks on the shaft TI is such that all of the substations are "picked up" during every revolution of the shaft. The gear ratio of the connection between 85 the impulse shaft IS and the transfer impulse shaft TI is such that during every revolution of the shaft IS, a cycle of transfer impulses will be sent through the units of a substation. As I have shown and described my system as arbitrarily comprising two substations, the gear connection between the shafts IS and TI is such that the latter makes one revolution while the other makes two revolutions. For three substations 90 the gear ratio between the shafts IS and TI would be 1 to 3, respectively, and so on for any number of substations. 95

Having already advanced a detailed description of the operation of the substation 100 units in connection with Fig. 8, I do not at this point deem it necessary to repeat such description in connection with the circuit arrangement shown in Fig. 2, since it will now be understood how the actuation 105 of the workmen's individual registers are duplicated in the proper classified-total registers at the final station. However, I have yet to call attention to the differential register represented by DR and diagrammatically indicated in Fig. 2 as having two sets of windings, one set being included in the connections leading from the grand total wage-register GTW and the other set 110 reversely included in the connections leading from the total wage-register TWW. The first set of windings is arranged in the order of a , b and c ; while the second set of windings is arranged in the order of b , a and c . This is precisely similar to the arrangement of the two sets of windings on the actuating mechanism shown in Figs. 3, 4 and 115 5. The armature of the differential register DR is adapted to actuate numeral wheels. I have not considered it essential to an understanding of my invention to illustrate this mechanical detail, since it is something 120 which can be readily worked out by any 125

one skilled in the art. The purpose of this differential register is to show the difference between the indications of the grand-total register G.T.W. and the indications of the 5 total waste-wage register T.W.W. If we regard the windings *a*, *b* and *c* of the register D.R. as actuating the same forwardly, the windings *b*, *a* and *c* actuate the same backwardly, the amount of forward actuation 10 will, of course, be the same as the amount of actuation of the register G.T.W. while the amount of backward actuation will be the same as the amount of actuation of the register T.W.W. The resultant actuation of the 15 numeral wheels of the differential register D.R. will be such as to indicate the difference between the actuations of the registers G.T.W. and T.W.W. The grand-total registers, as well as the differential register may be set 20 back to zero by throwing the switch 91 into engagement with the contacts 95, 96 and 97, and by moving the switches 90 into engagement with the contacts 98. This will close the circuit through the registers from the 25 one side of the battery B', to conductor 99, contacts 98, and from there across the switches 90 through the windings of the registers to bus-conductors 300*a*, 300*b*, 300*c*, to contacts 95, 96, 97, across the switch 91, 30 thence by means of the disks *t'**a*, *t''b*, *t'''c* to the other side of the battery. The actuation of the registers will, however, be in the reverse direction for the reason that when the switch is thrown into engagement with the contacts 95, 96 and 97, the order in which 35 the impulses are impressed upon the register windings is reversed. Whereas, during the accumulation of these registers the phases were impressed in the order of *a*, *b*, *c* when 40 the switch 91 engages the contacts 95, 96 and 97, the impulses are impressed in the order of *b*, *a*, *c*. This is brought about by connecting the contact 97 with conductor 300*c*, connecting contact 96 with the conductor 45 300*b*, and connecting contact 95 with the conductor 300*a*. As each register is brought back to the zero position the circuit through the register is automatically interrupted by the opening of a pair of associated contacts, as was explained in connection with Figs. 6 and 7. It is, of course, 50 unnecessary that there should be a separate battery for the transfer circuits. Conductors 92, 94 and 99 might as well be connected with the battery B. For the sake of 55 clearness, however, a separate battery has been shown in Fig. 2.

In the foregoing description of the preferred embodiment of my invention I have 60 not endeavored to enumerate all of the many advantages residing in the different features and arrangements, nor have I tried to set forth the many uses to which such features and arrangements might be put

other than the specific use herein described 65 for the purpose of conveying a clear understanding of my invention. It is, moreover, obvious that certain details and characteristics of my invention may be employed without the use of certain other features, and 70 that many modifications will be apparent to those skilled in the art without departing from the scope of the invention as defined in the appended claims.

Having thus described my invention, what 75 I desire to claim as new and secure by Letters Patent of the United States is:

1. In an electromagnetic device, the combination of a magnetic field-structure having polar extensions, an armature rotatable 80 between said polar extensions, a plurality of windings arranged upon said field structure, a source of current, and connections between said source and said windings whereby the resultant effect of the windings 85 upon the armature is cyclically equal to zero.

2. In an electromagnetic device, the combination of a magnetic field structure having polar extensions, an armature rotatable 90 between said polar extensions, a plurality of windings arranged upon said field structure, and means for energizing said windings in pairs to cause the resultant rotation of the armature to be zero. 95

3. In an electromagnetic device, the combination of a magnetic field structure having polar extensions, an armature rotatable between said polar extensions, two sets of 100 windings carried by said field structure, and means for cyclically energizing said windings in succession so that one set of windings causes rotation of the armature in one direction, while the other set causes rotation thereof in the reverse direction. 105

4. In an electromagnetic device, the combination of a magnetic field structure having polar extensions, an armature rotatable between said polar extensions, two sets of 110 windings carried by said field structure, means for cyclically energizing the windings of one set in succession to cause rotation of the armature in one direction, and means whereby said rotation of the armature closes the circuit through the windings 115 of the other set to cause the armature to rotate an equal amount in the opposite direction.

5. In an electromagnetic device, the combination of three electromagnets provided 120 each with a pair of windings, an armature associated with said electromagnets to be rotated thereby, a source of current, and connections between said source and said windings whereby the resultant effect of 125 said windings upon the armature is cyclically equal to zero.

6. In an electromagnetic device, the com-

- 5 bination of three electromagnets provided with two sets of windings, an armature associated with said electromagnets to be rotated thereby, and means for cyclically energizing said windings in succession so that one set of windings causes rotation of the armature in one direction, while the other set causes rotation thereof in the reverse direction.
- 10 7. In an accounting system, the combination of a plurality of individual wage-registers, a time-register electrically connected with each wage-register in series, a plurality of impulse receiving devices adapted 15 to be connected in series with said wage and time-registers, a source of electrical impulses for actuating said registers and devices, and a selector-mechanism serially included in the circuit connections between said 20 source and said registers for selecting the wage-registers for actuation one after the other.
8. In an accounting system, the combination of a plurality of individual wage-registers, a time-register electrically connected 25 with each wage register in series, a source of electrical impulses for actuating said registers, and a selector-mechanism serially included in the circuit connections between said 30 source and said registers for selecting the wage-registers for actuation one after the other.
9. In an accounting system, the combination of a plurality of individual wage-registers, a time-register electrically connected 35 with each wage-register in series, a plurality of impulse receiving devices adapted to be connected in series with said wage- and time-registers, a source of electrical im- 40 pulses for actuating said registers and devices, a selector mechanism serially included in the circuit connections between said source and said registers for selecting the wage-registers for actuation one after the other, 45 a rate mechanism for controlling the number of impulses through the register-circuits to actuate each wage-register at a predetermined rate, and means for actuating the time-registers at a uniform rate irrespec- 50 tive of the rate of actuation of the wage-registers.
10. In an accounting system, the combination of a plurality of substations each comprising wage-registers, time-registers 55 and impulse-receiving devices, there being a time register electrically connected with each wage-register in series, a source of electrical impulses for actuating said registers and devices, circuit-connections for 60 connecting a wage-register and its associated time-register in series with one of the impulse-receiving devices, the corresponding registers and impulse-receiving devices in the different substations being connected in 65 multiple with said source of impulses, and a

selector mechanism serially included in the connections between the source of impulses and the substations for successively selecting the wage-registers of each substation for actuation.

11. The combination of a plurality of substations each comprising individual wage-registers and one or more impulse receiving devices, a source of electrical impulses for actuating said registers and devices, circuit 70 connections for connecting a wage-register in series with an impulse-receiving device, the corresponding devices and registers in the different substations being connected in multiple with said source of impulses, and a selector mechanism serially included in the connections between the source of impulses and the substations for successively selecting the wage-registers of each substation for actuation.

12. In an accounting system, the combination of a plurality of substations each comprising wage-registers, time-registers and impulse-receiving devices, there being a time-register electrically connected with each wage-register in series, a source of electrical impulses for actuating said registers and devices, circuit connections for connecting a wage-register and its associated time-register in series with one of the impulse-receiving devices, the corresponding registers and impulse-receiving devices in the different substations being connected in multiple with said source of impulses, a selector mechanism serially included in the connections between the source of impulses and the substations for successively selecting the wage-registers of each substation for actuation, a common rate-mechanism for all of the substations for controlling the number of impulses through the register-circuits, and circuit connections between said rate-mechanism and said substations whereby the registers of any substation may each be actuated at any desired rate independently of the registers in the other substations.

13. The combination of a plurality of substations each comprising individual wage-registers and one or more impulse-receiving devices, a source of electrical impulses for actuating said registers and devices, circuit connections for connecting a wage-register in series with an impulse-receiving device, the corresponding devices and registers in the different substations being connected in multiple with said source of impulses, a selector mechanism serially included in the connections between the source of impulses and the substations for successively selecting the wage-registers of each substation for actuation, a common rate-mechanism for all of the substations for controlling the number of impulses through the register-circuits, and circuit connections between said rate-mechanism and said substations whereby the

registers of any substation may each be actuated at any desired rate independently of the registers in the other substations.

14. The combination of a plurality of substations each comprising wage-registers and impulse-receiving devices, a source of electric impulses for actuating said registers and devices, circuit connections between said source and said substations for connecting the registers of each substation in series but connecting the corresponding registers and devices of the different substations in multiple, and a selector-mechanism serially included in the connections between the source of impulses and the substations for successively selecting the wage-registers of each substation for actuation.

15. The combination of a plurality of substations each comprising wage registers and impulse-receiving devices, a source of electric impulses for actuating said registers and devices, circuit-connections between said source and said substations for connecting the registers of each substation in series but connecting the corresponding registers and devices of the different substations in multiple, a selector mechanism serially included in the connections between the source of impulses and the substations for successively selecting the wage-registers of each substation for actuation, a common rate-mechanism for all of the substations for controlling the number of impulses through the register-circuits, and circuit connections between said rate-mechanism and said substations, whereby the registers of any substation may each be actuated at any desired rate independently of the registers in the other substations.

16. In an accounting system, the combination of a wage register, a time register, a source of electric impulses for actuating said registers, circuit connections between said source and said registers for connecting the registers in series, a rate-mechanism included in said connections for causing actuation of the wage-register at any desired rate, and means for actuating the time-register at a uniform rate irrespective of the rate of actuation of the wage-register.

17. In an accounting system, the combination of a wage-register, a time-register, a source of electric impulses for actuating said registers, circuit connections between said source and said registers for connecting the registers in series, a rate mechanism included in said connections for controlling the number of impulses passing through the register-circuit in a predetermined period to cause actuation of the wage-register at any desired rate, and means for automatically locking the time-register against actuation at certain intervals to render certain of the impulses ineffective, whereby a uniform rate of actuation of the time-register is secured.

18. In an accounting system, the combination of a plurality of wage-registers, a source of electric impulses for actuating the same, a multiplicity of impulse-receiving devices comprising each of a plurality of windings and a rotatable armature adapted to be acted upon opposingly by the impulses sent through the windings, circuit connections for sending impulses through any one of said wage-registers and one of said impulse-receiving devices, circuit connections for simultaneously sending impulses through said impulse-receiving devices in a direction to counteract said first mentioned impulses, and a totalizing register in each of said last mentioned circuit connections adapted to be actuated by said counteracting impulses, whereby the actuations of each wage-register are totaled in one of said totalizing registers.

19. In an accounting system, the combination of an impulse receiving device comprising a plurality of windings and a rotatable armature, a source of electric impulses, circuit connections between said source and said windings for sending impulses through said windings to act opposingly upon the armature, a wage-register in the circuit-connections leading to certain of said windings, a totalizing register in the circuit-connections leading to the other of said windings, and controlling means included in the circuit-connections for causing an impulse to be sent through the totalizing register for every impulse passing through the wage-register.

20. In an accounting system, a plurality of individual wage registers, a source of electric impulses for actuating the registers, circuit-connections between said source and said registers for causing actuation of the registers one after the other, a plurality of totalizing registers, circuit connections between said source of impulses and said totalizing registers for simultaneous actuation thereof, an impulse-receiving device interposed in said circuit-connections for causing actuation of the totalizing registers proportionately to the sum of the actuations of the individual registers, said impulse-receiving devices consisting each of an electric motor having a single armature.

21. In an accounting system, the combination of a source of electric impulses, a plurality of individual wage-registers, circuit-connections between said source and said registers for actuating the registers one after the other, a common conductor located in said circuit-connections, a normally open switch in said common conductor, a rate-mechanism comprising a plurality of circuit-controlling members, circuit connections between said source and said controlling members, means for selecting any one of said members to control the circuit of a connected wage-register, and a switch-actuating device included in the circuit-connections of

said controlling members for closing said switch whenever a rate-controlling circuit is closed.

22. In an accounting system, the combination of a source of electric impulses, a wage-register adapted to be connected therewith for actuation, a normally open switch included in the register-circuit, a clock-governed circuit-controlling member adapted to

10 be connected with said source of impulses independently of the wage-register, and a switch actuating device included in the circuit of said controlling member for closing said switch whenever said circuit is closed,

15 whereby the rate at which the circuit of said controlling member is closed determines the rate of actuation of the wage-register.

23. In an electromagnetic device, the combination of a rotatable armature, field poles 20 for rotating the armature, and a winding for preventing rotation of the armature.

24. In an accounting system, the combination of impulse sending mechanism, a rotatable armature, actuating coils in circuit 25 with such mechanism around the armature, and a winding associated with one of such coils to render the field coils ineffective when such winding is energized.

25. In an accounting system, the combination of two impulse sending mechanisms, a rotatable armature, two sets of actuating coils around such armature, and connections extending from each mechanism to one set of coils, one set of coils adapted to operate 35 the armature in one direction and the other set of coils adapted to operate the armature in the reverse direction.

26. In an accounting system, the combination of two impulses sending mechanisms, 40 a rotatable armature, two sets of actuating coils around such armature, and connections extending from each mechanism to one set of coils, the direction of rotation of the armature being determined by the set of 45 coils placed in operative condition, the two sets of coils serving when simultaneously actuated to leave the armature unaffected.

27. In an accounting system, the combi-

nation of two impulse sending mechanisms, a rotatable armature, two sets of actuating coils around such armature, connections extending from each mechanism to one set of coils, the direction of rotation of the armature being determined by the set of coils placed in operative condition, and means for 55 limiting the rotation of the armature in one direction.

28. In an accounting system, the combination of two impulse sending mechanisms, a rotatable armature, two sets of actuating 60 coils around such armature, connections extending from each mechanism to one set of coils, the direction of rotation of the armature being determined by the set of coils placed in operative condition, and means for 65 limiting the rotation of the armature in one direction without interfering with its free and continued operation in the reverse direction.

29. In an electromagnetic device, the combination of a register, a rotary motor therefor, and means for rotating the motor a desired amount in either direction. 70

30. In an electromagnetic device, the combination of a register, a rotary motor 75 therefor, a first mechanism for rotating the motor a desired amount in one direction, and a second mechanism for rotating the motor a desired amount in the opposite direction.

31. In an electromagnetic device, the combination of a register, a rotary motor therefor, a first mechanism for rotating the motor a desired amount in one direction, and a second mechanism for rotating the 85 motor a desired amount in the opposite direction, simultaneous actuation of both of such mechanisms serving to produce no resultant effect on the register.

In witness whereof, I hereunto subscribe 90 my name this 13th day of September, A. D. 1909

WILLIAM J. CRUMPTON.
